HERBERT AUSTIN, OF BROMSGROVE, ENGLAND.

CROSS-SLIDE OF LATHES OF THE TURRET TYPE.

1,074,924.

Specification of Letters Patent.

Patented Oct. 7, 1913.

Application filed March 23, 1912. Serial No. 686,681.

To all whom it may concern:

Be it known that I, HERBERT AUSTIN, a subject of the King of Great Britain, and residing at Bromsgrove, in the county of Worcester, England, engineer, have invented certain new and useful Improvements Relating to the Cross-Slides of Lathes of the Turret Type, of which the following is a specification.

10 This invention relates to means of traversing, transversely of the bed, a cross-slide of a lathe of the turret type, having in view more particularly means for such purpose which will traverse the cross-slide in a direction at other desired angles to the lathe axis besides simply at right angles thereto.

In order that the invention may be clearly understood, I will now describe a convenient practical application thereof, which is illustrated by the drawings herewith.

Of the drawings:—Figure 1 is a transverse section through a portion of one side of the lathe bed, showing a side view of the cross-slide and the saddle which carries it. Fig. 2 is an outer view of the saddle and cross-slide shown by Fig. 1, and shows also, in side view the forward end of the turret-saddle and a portion of the turret. Fig. 3 is a plan view of the cross-slide and saddle and of a portion of the forward end of the turret-saddle and a portion of the turret. Fig. 4 is a transverse section through the upper portion of the lathe bed and an inner end view of the turret-saddle, showing the turret thereon. Fig. 5 is a section, to an enlarged-scale, of the saddle and cross-slide, taken on line $x-x$ of Fig. 1, and Fig. 6 is a sectional plan, to the same scale as Fig. 5, through the saddle only, taken on line $y-y$ of Fig. 2.

A is a saddle for the cross-slide, B the cross-slide, D a short vertical spindle, which is journaled within the saddle and is formed with or carries at its lower end a bevel-wheel d and carries at its upper end a pinion d' , and the bevel wheel d is driven by a bevel wheel e which is slidably fitted upon a horizontal shaft E, this shaft being journaled toward one end in a bearing E' of the saddle and journaled at its other end in a bearing at the headstock end of the bed, and being suitably operated from such latter end as required, and the bevel wheel e carries feather keys which engage with long grooves e' of the shaft E, and the pinion d' gears with a rack B' which is rigid with the cross-

slide B, all of which is analogous to mechanism which has previously been proposed for the purpose, and the rack is conveniently connected with the cross-slide such as in the manner in which a rack is described in the specification of my application for patent Serial No. 674872 with reference to Figs. 9 and 10 of the drawings accompanying such specification, as connected with a cross-slide to allow of its being adjusted endwise in relation thereto. As the shaft E is turned, it causes the slide B to move endwise, operating it through the medium of the bevel wheels e and d the pinion d' and the rack B'. If it is desired that the cross-slide shall be adapted to be traversed at different angles with the axis of the lathe, a turning-piece or rest C, upon which the slide is fitted to slide, is itself adapted to be turned in relation to the saddle and clamped in any position into which it has been turned, such as by means of T-headed bolts c fitted within a correspondingly-shaped annular groove c' formed up in the under face of the turning-piece C, and passing through a flange or ears a of the saddle, and the axis of this turning-piece is common with that of the vertical spindle D, in which case it follows that into whatever position the turning-piece C is turned to alter the inclination of the slide B in relation to the lathe axis, the pinion d' will always remain properly in mesh with the teeth of the rack B', and the slide will be moved endwise whether set at right-angles to the axis of the lathe or at other angle thereto. The saddle A will frequently be required to be securely fixed in relation to the lathe bed when it has been set endwise therewith into the position required for the work to be performed. The shaft E may be operated by any suitable mechanism which will turn it in opposite directions as required, such as by means of mechanism of the character described for a similar purpose in the said specification of my application for patent Serial No. 674872 by reference to Fig. 12 of the drawings therewith.

I will now describe means of moving the slide B inward toward the work, whether at right-angles thereto or at other angle as may be required, which are shown in the drawings as used in combination with the mechanism already described as analogous to mechanism previously proposed for the purpose and which, in such combination is

used only in moving the slide back. A worm-wheel f is fixed to the spindle D, conveniently in position, as shown, immediately above the bevel wheel d . A horizontal shaft F, which is slidably journaled within the saddle A, is formed with a worm f' which meshes with the teeth of the worm-wheel f . The shaft F is moved endwise by the turret saddle G coming against the end thereof during an advance movement in each cycle of operations, and the endwise movement of the shaft thus produced in relation to the saddle causes it to act as a rack in relation to the worm-wheel f and turn such wheel, and consequently the vertical spindle D, and move the slide B inward to the work. As it will usually be required that some of the forward movements of the saddle G shall be inoperative in relation to the shaft F, an opening g is formed in the saddle, which passes over the end of the shaft F for each forward movement of the saddle which is required to be inoperative in relation to the shaft. For each forward movement of the saddle, however, which is required to be operative in relation to the shaft, the free and thickened end h' of an arm h which is pivoted to the saddle is brought across the opening, and itself comes against the end of the shaft F during the forward movement of the saddle and moves the shaft as required. This arm is operated by the turret H during a turning movement of its cycle of operations, and for this purpose a pin k , which is screwed down through a lug k' of the turret, presses down, against the force of a spiral spring k^2 , a plunger k^3 which is slidably fitted within a hole of the turret saddle, and the plunger k^3 has a cross pin k^4 which engages with a slot of a portion of the arm h which extends rearward of the pivot axis of the arm. In Fig. 4 an arm h is shown both at the right-hand and left-hand sides of the lathe, one of them being for use in connection with a cross-slide which is mounted at the right-hand side of the lathe, and the other for use in connection with a cross-slide which is mounted at the other side of the lathe, providing that cross-slides are required at both sides of the lathe. The arm h at the left-hand side of the lathe is shown in its downward position clear of the corresponding opening g of the saddle, and the arm at the right-hand side of the lathe is shown to have been moved up, by the action of the pin k , into position with its thickened end h' across the corresponding opening g . The pin k is carried in such position in the turret H that it operates the arm to bring it into position across the opening g just as the turret is completing its turning movement which brings the pin k over the plunger k^3 , and the pin k remains over the plunger k^3 , holding it down,

while the turret then remains at rest in relation to the turret-saddle. The head of the plunger k^3 is rounded or slanted to enable the pin k to move over it and press it down as it does so, and the cross pin k^4 of the plunger operates within a vertical slot of the turret saddle, the upper end of which forms a stop to the upward movement of the plunger. Through the lug k' of the turret is shown to be screwed a second pin k^5 corresponding to the pin k , for the purpose of pressing down a plunger for bringing a lever h at the other side of the lathe into position across an opening g of the saddle, in a case in which it is required to have a cross-slide at each side of the lathe. Both the pins k and k^5 may be screwed sufficiently through the lug k' to insure that they will, respectively, press down in turn the plungers for the respective levers, or either of them only may be screwed through sufficiently for the purpose of pressing down the respective plunger, or both of them may be slackened back sufficiently to insure that neither plunger will be pressed down. As a matter of fact, in the arrangement shown, each pin k , k^5 , would press down each plunger, but either plunger would return, after being pressed down by the pin which was provided in respect of the other plunger, before the next forward movement of the turret saddle would take place, so that its being pressed down by such pin would be non-effective. If it is desired to throw the worm shaft F entirely out of action, and operate the cross-slide both outward and inward through the medium of the shaft E, the pin, which is carried by the turret in respect of such worm shaft, is screwed back to insure that at every forward movement of the turret saddle the hole g will pass over the end of the shaft F. The worm shaft F can be removed altogether if it is required to operate the slide entirely through the medium of the shaft E.

According to convenient means for enabling the shaft F to be turned so as to screw the worm f' through the teeth of the worm-wheel f and thereby adjust the shaft F endwise in relation to the worm-wheel, a bevel wheel m is carried within the saddle A in a manner which prevents it moving endwise but allows it to turn freely, the shaft F is slidable through the wheel m , a feather key of the wheel fitting within a long key-groove f^2 of the shaft, and a bevel wheel m' , which meshes with the bevel wheel m , is fixed upon a short spindle n which may be turned by hand. When the shaft F has been adjusted into the required endwise position in relation to the worm-wheel f , it is securely prevented from turning accidentally, such as by means of a set-pin p which is screwed down upon the boss of the wheel m and fixes such wheel against

turning. As the shaft E is, when the cross-slide is moved in by the shaft F utilized only in moving back the cross-slide from its work, the means by which it is operated from the head-stock end of the bed must, of course, be adapted for the purpose, as will be readily understood, such means allowing the shaft E to be turned in one direction while the vertical spindle D is being turned through the medium of a shaft F, and such means then operating to turn the shaft E in the reverse direction to bring back the cross-slide and thereby return the shaft F into position to be again operated by the turret-saddle.

Having fully described my invention, what I claim and desire to secure by Letters Patent, is:—

1. In a lathe of the turret type, a turret saddle slidable along the lathe bed, a tool-carrying cross-slide for operating transversely of the lathe axis, a saddle carrying such slide and itself carried by the lathe bed, a spindle carried by the cross-slide saddle, a rack of the cross-slide, means whereby said spindle is geared with said rack, a shaft which is parallel with the lathe bed, bevel gear through the medium of which said spindle is operated by such shaft and said slide thereby operated in one direction, and means for operating said slide in the opposite direction which comprise, a pinion of said spindle, a toothed rack which is slidably mounted in relation to the cross-slide saddle and meshes with said pinion and is moved endwise by the turret saddle and thereby operates the said pinion.

2. In a lathe of the turret type, a turret saddle slidable along the lathe bed, a tool-carrying cross-slide for operating transversely of the lathe axis, a saddle carrying such slide and itself carried by the lathe bed, a vertical spindle carried by the cross-slide saddle, means whereby said spindle operates said cross-slide, a shaft which is parallel with the lathe bed, bevel gear through the medium of which said spindle is operated by such shaft and said slide thereby operated in one direction, and means for operating said slide in the opposite direction which comprise, a pinion of said spindle, a toothed rack which is slidably mounted in relation to the cross-slide saddle and meshes with said pinion and is moved endwise by the turret saddle and thereby operates the said pinion.

3. In a lathe of the turret type, a turret saddle slidable along the lathe bed, a tool-carrying cross-slide for operating transversely of the lathe axis, a saddle carrying such slide and itself carried by the lathe bed, a spindle carried by the cross-slide saddle, means whereby said spindle operates said cross-slide, means for operating said spindle and thereby operating said slide in

one direction, means for operating said cross-slide in the opposite direction which comprise, a pinion of said spindle, a rack which is slidably mounted in relation to said cross-slide saddle and meshes with said pinion and is moved endwise by the turret saddle and thereby operates said pinion, an abutment which is carried by the turret saddle and means whereby said abutment will be automatically brought into the path of the last-mentioned rack when it is intended that a movement of the turret saddle shall move the said rack.

4. In a lathe of the turret type, a turret saddle slidable along a lathe bed, a tool carrying cross-slide for operating transversely of the lathe axis, a saddle carrying such slide and itself carried by the lathe bed, a spindle carried by the cross-slide saddle, means whereby said spindle operates said cross-slide, a pinion of said spindle, a rack which is carried entirely by the cross-slide saddle and is slidable in relation thereto and meshes with said pinion and is moved endwise by the turret saddle as a result of an abutment of the turret saddle coming against the end of the rack and thereby imparting to the rack the movement in one direction only of the turret saddle, and means whereby the spindle is operated in the reverse direction and itself operates the rack and returns it.

5. In a lathe of the turret type, a turret saddle slidable along the lathe bed, a tool-carrying cross-slide for operating transversely of the lathe axis, a saddle carrying such slide and itself carried by the lathe bed, a spindle carried by the cross-slide saddle, means whereby said spindle operates said cross-slide, a pinion of said spindle, a rack which is slidably mounted in relation to said cross-slide saddle and meshes with said pinion and is moved endwise by the turret saddle and thereby operates said pinion, an abutment which is carried by the turret saddle and means whereby said abutment will be automatically brought into the path of the last-mentioned rack when it is intended that a movement of the turret saddle shall move the said rack.

6. In a lathe of the turret type, a turret saddle slidable along the lathe bed, a tool-carrying cross-slide for operating transversely of the lathe axis, a saddle carrying such slide and itself carried by the lathe bed, a spindle carried by the cross-slide saddle, means whereby said spindle operates said cross-slide, a pinion of said spindle, a rack which is slidably mounted in relation to said cross-slide saddle and meshes with said pinion and is moved endwise by the turret saddle and thereby operates said pinion, an arm pivoted to the turret saddle, a tappet carried by the turret which, when adjusted in position for the purpose, moves the

arm in one direction, means whereby the arm is automatically returned when released from the tappet by the next turning movement of the turret, said arm coming, in one 5 of its extreme positions, into the path of the last-mentioned rack, and in its other extreme position, being clear of the path of such rack.

7. In a lathe of the turret type, a turret 10 saddle slidable along the lathe bed, a tool-carrying cross-slide for operating transversely of the lathe axis, a saddle carrying such slide and itself carried by the lathe bed, a vertical spindle carried by the cross-slide saddle, a rack of the cross-slide, means whereby said spindle is geared with said rack, means for operating said spindle and thereby operating said slide in one direction, means for operating said cross-slide 15 in the opposite direction which comprise, a pinion of said spindle, a rack which is slidably mounted in relation to said cross-slide saddle and meshes with said pinion and is moved endwise by the turret saddle and thereby operates said pinion, an arm pivoted 20 to the turret saddle, a tappet carried by the turret saddle which when adjusted in position for the purpose moves the arm in one direction, means whereby the arm is automatically returned when released from the 25 tappet by the next turning movement of the turret, said arm coming in one of its extreme positions into the path of the last-mentioned rack and in its other extreme position being clear of the path of such rack.

8. In a lathe of the turret type, a turret saddle slidable along a lathe bed, a tool-carrying cross-slide for operating transversely of the lathe axis, a saddle carrying such slide and itself carried by the lathe bed, a spindle carried by the cross-slide saddle, means whereby said spindle operates said 30

cross-slide, a worm-pinion of said spindle, a rack constituted as a bar having a screw thread therearound which meshes with the 45 teeth of the said worm-pinion and is carried entirely by the cross-slide saddle and is slidable in relation thereto and is moved endwise by the turret saddle as a result of an abutment of the turret saddle coming 50 against the end of the rack and thereby imparting to the rack the movement of the turret saddle, and means carried by said cross-slide saddle whereby said last-mentioned rack may be turned to screw its thread 55 through the teeth of the worm-pinion and thereby adjust the rack endwise in relation to such pinion.

9. In a lathe of the turret type, a turret saddle slidable along the lathe bed, a tool-carrying cross-slide for operating transversely of the lathe axis, a saddle carrying such slide and itself carried by the lathe bed, a spindle carried by the cross-slide saddle, means whereby said spindle operates the 60 cross-slide, a pinion of said spindle, a rack which is slidably mounted in relation to said cross-slide saddle and meshes with said pinion and is moved endwise by the turret saddle and thereby operates said pinion, an 65 abutment which is carried by the turret saddle and means whereby said abutment will be automatically brought into the path of the said rack when it is intended that a 70 movement of the turret saddle shall move 75 the said rack.

In witness whereof I have hereunto signed my name this 12th day of March 1912 in the presence of two subscribing witnesses.

HERBERT AUSTIN.
